UNITED STATES PATENT OFFICE.

LEWIS O. HENGGLI, OF OAKMONT, PENNSYLVANIA.

ANTICREEPER.

1,300,612.

Specification of Letters Patent. Patented Apr. 15, 1919.

Application filed November 21, 1918. Serial No. 263,626.

To all whom it may concern:

Be it known that I, Lewis O. Heneer, a citizen of the United States, and a resident of Oakmont, county of Allegheny, and State of Pennsylvania, have invented a new and useful Improvement in Anticreepers; and I do hereby declare the following to be a full, clear, and exact description thereof.

My invention relates to anti-creepers for use in railroad work whose purpose is to prevent the longitudinal creeping of the rail across the ties which bear the same.

The object of my invention is to provide a cheap, simple, and efficient form of anti-creep which can be easily manufactured at a small cost and which when applied to the railroad rail will perform its necessary functions during any change in climatic conditions, or during any vibrations caused by railroad trains moving upon the rails. Another object of my invention is to provide such a form of anti-creep as can be readily applied to the rails and as readily removed therefrom without the use of any special tools.

My invention consists, generally stated, in the novel construction as hereinafter more specifically set forth and described, and particularly pointed out in the appended claims.

To enable others skilled in the art to which my invention appertains to construct and use my improved anti-creep, I will describe the same more fully referring to the accompanying drawing, in which:

Figure 1 is a side elevation of my improved anti-creep constructed in accordance with my invention.

Fig. 2 is a plan view of the same.

Fig. 3 is an end view of the improved anti-creep showing the large loop on the top of the rail base and the gripping portion adapted to fit under the rail base.

Fig. 4 is another end view of the anti-creep looking from the opposite direction.

Fig. 5 is a side elevation showing the anti-creep about to be applied to the rail.

Fig. 6 is a side elevation showing the anti-creep applied to the rail.

Fig. 7 is a modification showing the same general form of anchor used with a key.

Fig. 8 is an end view of the same.

Like symbols of reference herein indicate like parts in each of the figures of the drawing.

As illustrated in the drawing my improved anti-creep "A" is formed from

sheet or plate metal which will give it exceeding strength over the cast anchor used largely at the present day. The sheet or plate is preferably pressed into shape and in the upper part of the same is an opening 1 for admitting the rail base "a."

This opening 1 is so shaped as to form the hooked shaped jaws 2 and 3 which fit over the respective sides of the rail base. The jaw 2 is substantially twice as long as the jaw 3 and its open portion 4 is somewhat wider than the open portion 5 of the jaw 3. The inner surfaces 6 and 7 of the jaws 2 and 3

approach each other at substantially the same angle as the top surfaces of the rail base approach each other, that is to say when the creep check or anti-creep is to be used with a 13° rail base the jaw surfaces

6 and 7 approach each other at substantially 75 154°. Intermediate its ends and nearer the jaw 3 than the jaw 2 the metal of the anti-creep "A" is bent outwardly as shown in

Figs. 3 and 4 to form a seat 8 for fitting against the bottom of the rail base "a." 80

This seat 8 is preferably formed by slotting the metal as at 9 and 10 and bending the intermediate portion 11 outwardly, thus providing a seat with a sufficient amount of

spring action for holding the anti-creep 85 firmly against the bottom of the rail base "a" as later explained. The proportion and shape of the seat 8 are such that it will be

within the line which would be formed by the bottom surface of the rail base, if the top surfaces of the rail base were made to

coincide with the jaw surfaces 6 and 7. This will be readily understood by reference to

Fig. 1 in which a rail base is indicated in dotted lines. When the anti-creep "A" is, 95

in position the seat 8 will be pressed or sprung downwardly as shown in Fig. 6 and will thus provide the necessary holding strength against the bottom of the base of

the rail. The jaw 3 is provided with a 100 curved portion 12 for increasing the bearing portion of the inner surface 7 of the same upon the rail base "a," while the jaw member 2 is provided with a more extensive

curved portion 13 for a like purpose. These 105 curved portions will also prevent any tilting of the anti-creep. At the end of the curved portion 13 is a shoulder or projection 14 for more securely holding the anchor in position on the rail base "a" as later explained.

The application of the anti-creep "A"

to the rail base "a" is similar to the application of a creep check shown in the United States Letters Patent No. 1,167,299 granted to me January 4, 1916. The jaw 2 is passed over the one side of the rail base "a" until its end engages with the top of said rail base and the anti-creeper "A" is then drawn upwardly until the seat 8 of the anti-creeper engages the bottom of the rail base "a" as shown in Fig. 5. It will be seen from this figure that it will be impossible to move the jaw 3 onto the upper side of the rail base nearest the same without distortion of the seat 8 bearing against the rail base. This operation is completed by driving the anti-creeper transverse of the rail base by means of a sledge hammer or the like applied to the outer surface "B" of the anti-creeper, whereupon the curved portions 12 and 13 will have their inner surfaces 7 and 6 respectively bearing upon the upper faces of the rail base "a" with the intermediate portion 11 bearing against the bottom of said rail base, and the shoulder or projection 14 will drop over and bear against the outer edge of the rail base to further prevent its becoming loose or displaced. During the application of the anti-creeper "A" to the rail base "a" and its passage from the position shown in Fig. 5 to that shown in Fig. 6, the seat 8 has been gradually displaced downwardly and when the final position is reached, sufficient spring action is exerted by said seat against the bottom of the rail base "a", together with the action of the inner surfaces 6 and 7 on the upper portion of the rail, to firmly and securely bind the same in position. In fact, the tendency of the intermediate portion 11 to return to its original shape results in an extremely strong gripping action on the rail base and such action is much more than sufficient to hold the anti-creeper in position regardless of any vibration to which the rail is subjected, or in spite of weather changes or other influences.

The anti-creeper "A" is so placed that its one side "a" will abut against a tie and at that side of the tie opposite to the direction in which there is a tendency for the rail to creep. The anti-creeper by its gripping action thus prevents any longitudinal movement of the rail across the tie.

Figs. 7 and 8 show a modification wherein the anti-creeper "A" is constructed precisely the same as that shown in the other figures of the drawing, except that the seat 8 in Fig. 1 is eliminated and a bearing surface 15 made to conform with the taper of the key 16, which is driven between said bearing surface and the bottom of the rail base "a". This form of anti-creeper is placed upon the rail with the inner faces 6 and 7 bearing upon the rail base "a" and the shoulder or projection 14 bearing against

one side of the rail flange whereupon the key 16 is driven between said surface 15 and the bottom of the rail base "a" until the outer end 17 of said key has passed the outer line of the open portion 4 of the anti-creeper, when the outer end 17 of said key will be pressed or driven over in order that it may pass into the opening of the jaw 2 and will engage the outer edge of the metal forming the open portion 4 and thus prevent its removal by vibration or other influence. 75

It will be readily seen that the driving action against the end 17 of the key 16 will distort the intermediate portion 11 of the anti-creeper precisely in the manner that the seat 8 of such portion will be deflected by the driving action against the side "B" of the anti-creeper "A" shown in Fig. 5, and thus the key 16 bearing against the bottom, and the inner surfaces 7 and 6 of the curved 85 portions 12 and 13 of the jaws 3 and 2 will grip the rail base "a" and hold it in the same manner as above described.

The anti-creeper as shown and described is extremely simple and easy of manufacture 90 and can be applied to the rail base in a very short space of time. Its removal is a matter of like simplicity.

It will also be readily apparent that a single use of the anti-creeper will not impair 95 its usefulness as it may be applied again and again if so desired.

It will also be readily seen that when once applied to the rail the anti-creeper will not become loose, nor will it shift longitudinally 100 on the rail base, as the gripping action is many times greater than the amount necessary to overcome any vibrations, changes in atmospheric conditions, etc.

What I claim as my invention and desire 105 to secure by Letters Patent is:—

1. An anti-creeper for rails comprising a plate having an intermediate flared-out bearing portion for engaging with the bottom of the rail base, and terminal gripping jaws 110 formed on the plate for securing said anti-creeper to the rail base, said anti-creeper being adapted to be moved transversely on the rail base, whereby the jaws may be tightened on said rail base. 115

2. An anti-creeper for rails comprising a plate having an intermediate flared-out bearing portion for engaging with the bottom of the rail base, and terminal gripping jaws having increased curved bearing faces 120 formed on the plate for securing said anti-creeper to the rail base, said anti-creeper being adapted to be moved transversely on the rail base, whereby said jaws may be tightened on said rail base. 125

3. An anti-creeper for rails comprising a plate having an intermediate flared-out bearing portion for engaging with the bottom of the rail base, and a pair of terminal jaws disposed so as to rigidly engage the top of the 130

rail base when said body is moved transversely of said rail base, whereby the intermediate flared-out bearing portion is distorted within its elastic limit thereby retaining said anti-creeper in position on the rail base.

4. An anti-creeper for rails comprising a plate having a pair of terminal jaws disposed so as to rigidly engage the top of the rail base when said body is moved transversely of said rail base, and a flared-out portion for exerting a gripping spring action upon the bottom of the rail base when said anti-creeper is in position.
- 15 5. An anti-creeper for rails comprising a

plate having a pair of terminal jaws with extended curved bearing faces, disposed so as to rigidly engage the top of the rail base when said body is moved transversely of said rail base, and a flared-out portion for 20 exerting a gripping spring action upon the bottom of the rail base when said anti-creeper is in position.

In testimony whereof, I, the said LEWIS O. HENGGI, have hereunto set my hand in the 25 presence of two attesting witnesses.

LEWIS O. HENGGI.
